UNITED STATES PATENT OFFICE.

RAYMOND D. SMITH, OF EAST MILTON, MASSACHUSETTS, ASSIGNOR TO TREMONT PRODUCTS CORPORATION, OF BOSTON, MASSACHUSETTS, A CORPORATION OF MASSACHUSETTS.

RELEASEABLE TIMER MECHANISM.

Application filed December 10, 1917, Serial No. 206,451. Renewed January 27, 1922. Serial No. 532,261.

To all whom it may concern:

Be it known that I, RAYMOND D. SMITH, a citizen of the United States, residing at East Milton, in the county of Suffolk and 5 Commonwealth of Massachusetts, have invented certain new and useful Improvements in Releasable Timer Mechanism, of which the following is a specification.

This invention relates to mechanism for 10 timing the automatic movement of a tension impelled device, such, for example, as that of a port-control plug of a gas valve or a movable contact member in an electric switch.

15 The invention will be best understood by reference to the following description when taken in connection with the accompanying illustration of one specific embodiment thereof, while its scope will be more particularly 20 pointed out in the appended claims.

Fig. 1 is a front elevation of my timer mechanism shown, merely for sake of illustration, as applied to an ordinary gas valve utilizing as a port-control device the usual 25 tapered and spring-seated rotatable plug,— the valve being shown in its closed position and with casing and certain exterior controlling and indicating parts removed.

Fig. 2 is a plan view of this valve and timing mechanism, showing the parts, partially 30 sectioned or broken away, as they are positioned in Fig. 1.

Fig. 3 shows in front elevation certain 35 portions of the casing and parts exterior thereof, and further shows the valve in its open position and the timer parts normally positioned and entirely free of operative relation to the valve.

Fig. 4 is a perspective view illustrating 40 more clearly the co-operative relation of certain principal elements of my invention, and shows the parts in the same positions as Fig. 3.

Fig. 5 is a similar perspective view but 45 showing the valve cocked and under tension tending to effect automatic movement thereof, certain of the parts being broken away to indicate more plainly their construction.

Each part when appearing in different 50 views of the drawing is designated by the same reference numeral and is so referred to in the following description.

The tapered valve plug 12 is held rotatably by the spring 13 in its seat in the valve body 10 and is prolonged forwardly in a 55 valve operating stem 14, of decreased diameter. On this stem, near its forward end, is fixed an operating plate 16, to a rearward extension 24 of which, is anchored one end of a powerful band spring 21. The other, 60 or inner, end of spring 21 is fast to the hub 18 of the control arm 19, which hub is free to rotate on, and relative to, the stem 14 except for the connection of spring 21, that normally maintains said arm 19 and said 65 extension 24 in abutting engagement.

Arm 19 pivotally carries a bell-crank latch lever 25, normally positioned by spring 22 for holding engagement with a fixed stud 28 thereby to lock said arm in its depressed 70 position as shown in Figs. 1 and 5, said latch having an actuating arm 27 terminating below the handle 20 at the end of control arm 19 as a convenient means of releasing said latch lever from engagement with said stud 75 against the action of spring 22.

The operating plate 16 carries pivotally mounted thereon, a projecting finger 30, said finger being impelled by the spring 26 to a position abutting against a hub portion 31 80 of the plate 16. The purpose of the resilient positioning of finger 30 for yielding movement in one direction to its broken line position as shown in Fig. 3, will hereinafter 85 be explained.

Between the valve body 10 and the actuating parts for the valve plug 12 just described, is a face plate 36 that has a portion extending laterally to the left and forwardly, to afford a pivotal mounting 37 for 90 a swinging detent lever 35. This detent lever is normally impelled by a spring 39 to a position as shown in full lines in Figs. 3 and 4, but engages with stop lugs 33 and 34 to limit its swing respectively in each direction, and also has a projecting spur 38 that, in the position of said lever shown in Figs. 1 and 5 is adapted to engage with the finger 30 to prevent valve closure, or clockwise rotation of the valve stem 14 from its 100 position shown in Fig. 3. Rotation of said stem in the other direction to said position will not, however, be prevented by spur 38 in the latter position of the detent lever be-

cause of the before mentioned one-way yielding of projection finger 30.

The swinging movement of detent lever 35 operates to lock and release the valve stem 14 from its position in Fig. 3, and said swinging movement is under government of a clock mechanism that rotates the timer element, or cam 40. The timing mechanism as a whole is supported by a main back-plate 47, 10 extending to the left from the valve body 10, and such mechanism, in the present instance, is composed merely of an ordinary balance-wheel clock-movement constructed, however, with the timer element or cam 40 fixedly connected, as is also one end of the clock spring 50, to the winding shaft 43, on which loosely turns the large clock gear 54. This shaft, together with the other clock gear spindles, is pivoted between the clock-movement frame 15 plates 45 and 46.

A well known type of friction imparted, pawl-and-ratchet connection between the large gear 54 of the clock-movement and the said winding shaft 43, is of such frictional 25 strength as to enable the escapement train to hold back the shaft as impelled by the clock spring 50. Such frictional connection, however, permits more forceful manual turning of this shaft in either direction of rotation 30 which simultaneously winds or unwinds the clock spring 50 to a proportional degree and causes similar rotation of the cam 40, whereby a notch, or recess, 49 in the periphery thereof, is displaceable to a desired degree 35 from its position shown in Fig. 3, in which figure the rearwardly turned end 32 of detent lever 35 is shown as seated in this cam notch 49 by action of spring 39.

It will be clear that, whereas not necessarily the case, the detent lever 35 in this particular embodiment of my invention, when seated as above described, locks the cam 40 against rotary movement. For this and other reasons I have devised a tripping 40 mechanism next to be described which automatically releases the cam 40 from this lever before said cam is rotatively adjusted to desired time setting in the usual manner.

The cam 40 is carried on an enlarged, 50 forwardly-extending portion 42 of the winding shaft 43. This enlarged portion carries fixed to its extreme forward end a pointer-hand 53, and between this pointer-hand and said cam, is mounted for a limited degree of 55 rotary movement (relative to the shaft portion 43 and to the cam 40 and pointer 53 fixed thereto) a hub 51, from the end of which adjacent said cam, extends to the left an arm 52 carrying a pin 55 that engages 60 with a slot 56 in the cam 40 and limits the rotative movement of hub 51 relative to the said cam in both directions. Opposite the arm 52 is fixedly carried by said hub 51, a tripping arm 60, that co-operates with an 65 idler tripping finger 61 pivoted at 62 to the

forward face of cam 40. A spring 64 impels this tripping finger counter-clockwise and against the tripping arm 60, normally to maintain these parts in their position shown in Figs. 3 and 4.

The forward end of hub 51 carries fixed thereto a handle-carrying arm 65, that is preferably positioned to extend in the opposite radial direction from the pointer 53 and to be substantially in diametrical alignment therewith when hub 51 is normally positioned by the stop pin 55 and spring 64, as described. The pointer-hand 53 carries a forwardly projecting handle 68 and the arm 65, a similar handle 69.

A casing 70 is provided, and mounted exterior thereof is a dial 71 marked to co-operate with the pointer-hand 53 always to indicate the true rotative position of cam 40, said dial being preferably graduated to indicate the time that will be consumed in the return of said cam to its valve releasing position in Fig. 3, after its displacement from such position for locking the detent lever 35. A stop pin 59 engages the pointer 53 to stop clockwise travel of the latter when cam 40 has reached its position to permit entrance of the end 32 of detent lever 35 into the cam notch 49.

On the forward extremity of the valve stem 14 and exterior of the casing 70 is fixedly mounted a wing nut 63 that serves co-operatively with appropriate markings on another casing carried dial, to indicate the true port-controlling position of the valve plug 12 and incidentally to serve as actuating means for same in case of accident to the spring-connected control arm 19.

The full co-operation of the parts heretofore described will now be explained.

With the timer element or cam 40, positioned as in Fig. 3, the valve plug 12 is free to be oscillated, by the spring and abutment connected control arm 19, in either direction, thereby to be normally established in any desired port-controlling position. When, however, it be desired to effect, say, a time-controlled closure of the valve, the pointer 53 is turned counter-clockwise by pressure on handle 68 in direction of arrow A and by simultaneous pressure on handle 69 in direction of arrow B. It will be apparent that such pressure may conveniently be imparted by use of the thumb and forefinger. Such manipulation initially results in the rotative displacement of handle arm 65 relative to pointer 53 as indicated by broken lines in Figs. 3 and 5 and in the consequent movement of tripping arm 60 and idler finger 61 against the action of spring 64 to displace lever 35 from cam notch 49 as shown in Figs. 1 and 5. Stop pin 55, at this time, however, comes into engagement with one end of slot 56 so that further pressure as described on handles 68 and 69

will turn the now freed cam 40 counter-clockwise to the desired time setting. Upon release of the handles 68 and 69 the now energized clock spring will operate under its escapement retarded action, slowly to rotate the cam clockwise, and finally to return the same, after the determined interval of time, to its position permitting entrance of detent lever 35 into notch 49. Or, if desired, 10 cam 40 may be manually and directly returned to this position by pressure on handles 68 and 69 in clockwise direction. The operative effect upon the valve of the operation just described is obviously that during 15 such time as detent lever 35 is held by the periphery of cam 40 in the position of said lever shown in Figs. 1 and 5 no movement of the valve from its position as in Fig. 3 can occur, but said valve may be tensioned 20 for such closing movement by displacement relative thereto of control arm 19 to its locked position shown, in broken lines, Fig. 3, and in full lines Fig. 5 which displacement establishes tension in spring 21 tending to 25 cause the time-governed, automatic, follow-up movement of the valve stem 12 and plate 16 to their position as in Fig. 1 to close the valve.

It will be apparent to those skilled in the 30 art that my invention may have useful application to timed devices other than those limited to oscillatory movement as in the simple form of gas valve disclosed herein merely to demonstrate the operative principles involved; and it will be readily apparent that many departures may be made from the exact arrangement of parts that I have herein chosen to disclose as a preferred embodiment. For instance, mechanism for 35 vesting the control of a manually settable timer element (such as cam 40) and the control of a co-operating detent member (such as lever 35) in a common instrumentality (such as handles 68 and 69) convenient for simultaneous manipulation, say, by a single hand of the operator, may have uses other than to free such timer element from such detent; and for serving other purposes 40 may be suitably modified in various details entirely within the spirit of my invention, of which the herein described embodiment is but illustrative. I therefore do not limit the scope of my invention to such specific embodiment but what I claim is:

65 1. In a timing apparatus, in combination; a timer element having slow-acting power means automatically to impel it to a stop-limited position; a detent normally urged to a position for co-operative engagement with said element; a device to be timed by said element through the action of said detent, said device being tensionable for automatic movement and restrainable from said movement by said detent when the latter is displaced from its said position; control means

connected with said element for manually setting the same away from its stop-limited position thereby temporarily to lock said detent so displaced; and mechanism actuatable through manipulation of said control 70 means to displace said detent from its said position.

2. In apparatus-timing mechanism embodying a manually displaceable and automatically returnable timer element having a recessed portion arranged in normal position of the timer element to receive a movable apparatus-controlling detent so that engagement of said detent with the recessed portion of said element holds the latter from movement; the combination with said element of a time-pointer mounted to move in unison therewith and relative to a cooperatively graduated stationary time-dial; a handle having lost motion engagement with said element for shifting the latter to and from its said normal position; and means actuated by movement of said handle relative to said element and time-pointer to free the recessed portion of said element from interceptive engagement by said detent. 80

3. In a timing mechanism embodying a power driven timer element adapted to govern the automatic movements of a timed device by restraining and releasing an interposed detent member mounted to swing to a position for simultaneously locking said element and releasing said device, the combination with said element and detent, of an operating extension for rotatively adjusting said element; and a tripping device arranged to be actuated by said operating extension thereby to free said element from said detent to permit rotative adjustment of the element. 100

4. In a timing mechanism embodying a power driven timer element adapted to govern the automatic movements of a timed device by restraining and releasing an interposed detent member mounted to swing to a 110 position for simultaneously locking said element and releasing said device, the combination with said element and said detent; of an operating extension movable relatively to said element and having positive engagement therewith in both directions of movement whereby said element may rotatively be adjusted by said extension; and a tripping device arranged to be actuated by movement of said operating extension relative to said element thereby to free the latter from said detent to permit its rotative adjustment. 115

5. In a timing mechanism embodying a power driven timer element adapted to govern the automatic movements of a timed device by restraining and releasing an interposed detent member mounted to swing to a 125 position for simultaneously locking said element and releasing said device, the com-

- bination with said element and said detent, of an operating extension for rotatively adjusting said element; and a tripping mechanism carried partly by said element 6 and arranged to be actuated by said operating extension thereby to free said element from said detent to permit rotative adjustment of the element.
6. In combination with a timer element 10 that is arranged to restrain and to permit movement of a detent, in respectively different positions of said element, and that is further arranged to be locked by said detent when in a position to permit said movement 15 of same; a compound actuating handle, one part of which is fixed to said element and formed as a pointer-hand to indicate the rotative position thereof, and the other part of which is arranged for limited movement 20 relative to said first part and to said element; together with a trip actuatable by said relative movement of said other handle part and thereby rendered operative to free said element from said detent.
- 25 7. Mechanism for manually actuating, at once, a motor-driven timer element and a detent member co-operating therewith, said mechanism embodying in combination; two concentrically pivoted and relatively swing- 30 able control arms adapted for simultaneous manipulation and normally positioned substantially in opposite radial alignment by spring connection there between; operating connection between one of said handles and 35 said detent whereby relative movement of said handles actuates the detent; and operating connection between said handles and said element whereby movement of said handles in unison impels said element to 40 different operative settings.
8. Mechanism for manually actuating both a motor-driven timer element and a detent member co-operating therewith, said mechanism embodying in combination; two concentrically pivoted and relatively swing- 45 able control arms adapted for simultaneous manipulation and normally positioned in designed rotative relation by spring connection there between; operating connection between one of said handles and said detent whereby movement of said handles relative 50 to each other actuates the detent; and operating connection between said handles and said element whereby movement of said handles in unison impels said element to 55 different operative settings.
9. In combination; a spring-positioned 60 detent; a timer element arranged in respectively different positions thereof to prevent and to permit movement of said detent to its spring-urged position; a compound handle for manually actuating said timer element, one part of which handle is fixedly connected to said element and arranged to 65 indicate the rotative position thereof, and the other part of which handle is arranged for limited movement relative to said first part and to said element; and tripping mechanism operatively related to said detent and actuatable by relative movement between said two parts of the compound handle thereby to displace said detent from its spring-urged position.
- 70 10. In combination with a resiliently positioned detent lever and a rotary timer 75 disc peripherally formed to prevent and to permit at successive rotative positions, movement of said lever substantially radially of said disc, said lever being normally urged to a position to engage with said disc so as to prevent the latter's rotation; manipulative means pivoted concentrically with said disc and connected to rotate the same partially through lost-motion engagement therewith; and co-operating devices actuatable through movement of said means relative to disc thereby to retract said detent lever from restraining engagement with said disc.
- 80 11. In combination; a valve stem tensionable for rotative movement to a stopped position; a slow-moving device automatically rotatable for timing said movement of the valve stem; a detent member resiliently positioned normally to prevent rotary movement of said device and shiftable into interceptive engagement with a fixed extension on said stem; time-indicating means including a graduated dial, a part of said means being rotatable with said device for indicating its degree of displacement from said stopped position; and a resiliently connected control-instrumentality having lost-motion engagement with said device and arranged by limited movement relative to the latter and to said means to shift said detent member into the path of said stem extension, said element being further arranged so that continued movement thereof impels said device through designed 90 operative settings.
- 90 100 12. In a timing apparatus, in combination; a timer element having slow-acting power means to impel it automatically to a stop-limited position; a detent normally urged to a position co-operatively to engage with said element; a device adapted to be timed by said element through movement of said detent; manipulated control means connected with said element for manually shifting the same away from its stop limited position thereby to limit the movement of said detent; and mechanism actuatable through manipulation of said control means directly to move said detent.
- 105 110 13. In a timing apparatus, in combination, a device to be timed with means for tensioning it for automatic movement, a detent, a timing element normally interlocked with the detent, and means to disengage the detent from the timing element.
- 115 120 125 130
